UNITED STATES PATENT OFFICE.

CLARENCE W. COLEMAN, OF WESTFIELD, NEW JERSEY, ASSIGNOR TO THE HALL SIGNAL COMPANY, A CORPORATION OF MAINE.

RAILWAY-SEMAPHORE.

No. 882,930.

Specification of Letters Patent.

Patented March 24, 1908.

Application filed October 31, 1905. Serial No. 285,273.

To all whom it may concern:

Be it known that I, CLARENCE W. COLEMAN, a citizen of the United States, residing at Westfield, in the county of Union and State of New Jersey, have invented certain new and useful Improvements in Railway-Semaphores, of which the following is a specification, reference being had therein to the accompanying drawing, forming a part thereof.

My invention relates to semaphores such as disclosed in the Loree and Patenall Patent No. 733,981, dated July 21, 1903, wherein a semaphore-blade moves through the upper 15 quadrant and the weight of snow and ice upon the semaphore-blade, instead of being an element of danger, is an element of safety increasing the normal tendency of the semaphore to danger position.

My invention has for its objects to provide a semaphore of this class in which the signal-lamp, which coöperates with the spectacles of the semaphore to give the light indications for night signals, is located on top of the 25 signal-post or support, permitting a single signal-lamp to be employed for two semaphores controlling traffic in opposite directions, as in a large proportion of single track work and for station and train-order signals, 30 and also to provide such a semaphore in which the spectacle portion is largely disposed at the side of the support opposite that at which the blade is located in all positions of the semaphore, permitting the gravitational forces exerted by the semaphore-blade and the spectacle portion to be opposed 35 to each other without impairment of the effect of snow and ice in increasing the normal tendency of the semaphore to the danger 40 position.

My invention also has for its object to provide a semaphore adapted for coöperation with a signal-lamp at the top of the support and also with a signal-lamp at the side of the 45 support opposite that at which the blade is located.

Other objects of my invention will appear from the following description of the apparatus embodying my invention which is illustrated in the accompanying drawings. I will now describe such apparatus and will thereafter point out my invention in the claims.

Figure 1 is a front elevation of the upper 55 part of a semaphore-post, with two sema-

phores thereon for traffic in both directions, both semaphores being shown in the danger positions. Fig. 2 is a plan view of the same, with the post in section. Fig. 3 is a front elevation of the parts shown in Fig. 1, with the front semaphore in the safety or clear position and the rear semaphore in the caution or distant-danger position. Fig. 4 is an enlarged vertical section of the front semaphore-blade, taken on the plane indicated by the line 4—4, Fig. 1. Fig. 5 is a front elevation of a single semaphore and the upper part of its semaphore-post, with the signal-lamp located at the side of the post opposite that at which the semaphore-blade is located. Fig. 6 is a front elevation of a semaphore-post, with two semaphores thereon, for traffic in both directions, the semaphores being of modified construction with separate semaphore-blades and spectacle portions secured together, the signal-lamp on top of the post, and both semaphores at clear and arranged to be pulled to such position by a wire or other tension means.

I will first describe the construction shown in Figs. 1 to 4, inclusive. Here the semaphore-post *a* is of ordinary construction, and the signal-lamp *b* is on top of the post so that a single signal-lamp is adapted for use with two semaphores such as shown, arranged for traffic in opposite directions. The front semaphore, with its semaphore-blade at the right side of the post, comprises the blade *d* and the spectacle portion *e*, these two portions of the semaphore being made integral or in one piece of sheet metal, as sheet-iron or steel, beaded at its edges, as usual in sheet-metal work, and having the pivot-boss *f*, which may be welded or riveted thereto. Four spectacle-openings, *g*, *y*, *r* and *o*, are formed in the spectacle portion, three of which, *g*, *y* and *r*, are located so as to co-operate with the signal-lamp *b*, on top of the post, in the different positions of this semaphore. The spectacle-openings *y*, *r* and *o* are located so as to co-operate with a signal-lamp located at the side of the post opposite that at which the semaphore-blade is located, such an arrangement of signal-lamp being shown in Fig. 5 and the signal-lamp *b* there shown being supported on a bracket in the usual manner, but located above the pivot of the semaphore. Spectacles of colored or colorless glasses may be fitted in these spectacle-openings in any desired 110

manner, or the spectacle-openings may be partly unprovided with spectacles, as may be desired, to adapt the semaphore to use as a three-position signal, a two-position home-
5 signal, a two-position distant-signal, a switch-signal, a train-order signal, or to any of the uses of a railway signal, and to adapt the semaphore to use either with the signal-lamp on top of the post as shown in Figs. 1 to 10 4 inclusive, or with a signal-lamp at the side of the post as shown in Fig. 5.

As shown in Figs. 1 to 4, inclusive, spectacles are provided in the three openings, g , y and r , which may be green at g for safety, yellow at y for caution and red at r for danger; and as shown in Fig. 5 spectacles are provided in the openings y , r and o , green at y for safety, yellow at r for caution and red at o for danger.

20 The rear semaphore in Figs. 1, 2 and 3, which has its blade at the left side of the post, comprises the blade d' and the spectacle portion e' , having a pivot-boss f' and four spectacle-openings, g , y' , r' and o' .
25 This rear semaphore is of exactly the same construction as the front semaphore already described. The semaphores are secured on shafts j and j' , respectively, on which are also secured cranks k and k' , respectively, and operating up-and-down rods p and p' , respectively, are secured to the cranks and operate to push the signals to clear under the control of automatic or manually operated mechanisms, as may be desired, with lever, gas, 30 pneumatic, electrical or other operating mechanisms. The semaphores gravitate from the upper vertical or clear position, shown as that of the front semaphore in Fig. 3, through the oblique or caution position, 35 shown as that of the rear semaphore in Fig. 3, to the horizontal or danger position, shown as that of both semaphores in Figs. 1 and 2. The movements of the semaphores are arrested in the danger positions by stop-screws 40 q , q^2 , respectively, which come in contact with the respective cranks k , k' , when the semaphores reach their danger positions. Jam-nuts q' and q^3 , respectively, lock the stop-screws in the positions to which they 45 are adjusted.
50

The arrangement of the signal-lamp on top of the post or support permits a single lamp to be employed for two semaphores and is desirable wherever two semaphores on the 55 same post are employed for traffic in both directions, as in a large proportion of single track work, and in train-order and station signals. Such an arrangement requires the location of the spectacle-openings largely 60 above the pivotal center of the semaphore, and where the semaphore-blade moves downward from safety to danger, through the upper quadrant, this construction involves the movement of the safety and caution spectacles over the pivotal center to-

ward the blade side of the pivotal center. Where a metallic semaphore-blade is employed, the blade itself is of considerable weight, and if unbalanced would require the expenditure of considerable power to raise it from the danger to the safety position, which with an automatic operating mechanism would be a serious objection, and where the blade and spectacle portion are integral, a metallic blade is desirable and, indeed, a 75 metallic blade is for many reasons preferable to a wooden blade, the wooden blade having heretofore been so extensively used by reason of its lightness, a desirable feature in semaphores elevated to danger by counter weight- 80 ing spectacle portions.

My improved semaphore above described has the weight of its spectacle portion disposed largely on the side of the pivotal center opposite that at which the blade is 85 located so that at all times the weight of the blade is to some extent counterweighted. As characteristic of semaphores of the type to which my invention relates, the presence of snow and ice on the semaphore-blade 90 only increases the normal tendency to danger, it being noted that on the side of the semaphore opposite the blade side of the pivot no portion of the semaphore extends far from the pivotal center, so that snow and 95 ice on that side of the semaphore would not be of importance.

In the modified construction of semaphore shown in Fig. 6, the signal-lamp is also located on top of the post and adapted to coöperate 100 with the spectacles of two semaphores, one for each direction of traffic. Here each semaphore is made of two pieces, the spectacle portion e^2 and the blade d^2 , the spectacle portion being a comparatively heavy metallic part or casting and the blade of light material, as wood, the blade being bolted to the spectacle portion in the usual manner. Three spectacle-openings are here shown, g^2 , y^2 and r^2 . The operating means here shown 110 is a wire l , which is secured to the crank k and operates to pull the semaphore to clear. The spectacle portion is separately counterweighted so as to go to danger independently of the blade so as to guard against the possibility of a clear signal at the spectacle portion, when a danger signal should be given in the event of the detachment or breaking off of the blade, this weighting or counterweighting being provided by the thickened 115 portion e^3 . Here the spectacle-openings swing above the pivot toward the blade side of the pivot, but the weighted part e^3 swings downward toward the vertical line through the pivot as the semaphore moves from 120 safety to danger, and the resultant gravitational force exerted upon the semaphore to move it to the danger position approximates a constant quantity in all positions of the 125 semaphore.

It is obvious that various modifications may be made in the constructions shown and above particularly described within the principle and scope of my invention.

5 What I claim and desire to secure by Letters Patent is:—

1. The combination, with a semaphore-support, of a semaphore including a semaphore-blade and spectacle portion, the semaphore being pivotally mounted on a center at one side of the blade, and a signal-lamp located on top of the support, the spectacle portion of the semaphore having spectacle-openings disposed so as to coöperate with the lamp in both the upper and the lower positions of the blade and the semaphore being arranged so that the blade is at one side of the pivotal center when the semaphore is in the safety position and moves downward at that side of the pivotal center from the safety to the danger position.
2. The combination, with a semaphore-support, of a semaphore including an integral semaphore-blade and spectacle portion, the semaphore being pivotally mounted on a center at one side of the blade, and a signal-lamp located on top of the support, the spectacle portion of the semaphore having a spectacle-opening disposed so as to coöperate with the lamp and the semaphore being arranged so that the blade is at one side of the pivotal center when the semaphore is in the safety position and moves downward at that side of the pivotal center from the safety to the danger position.
3. The combination, with a semaphore-support, of a semaphore including a semaphore-blade and spectacle portion, the semaphore being pivotally mounted on a center at one side of the blade and arranged relatively to its pivotal center so that the blade

is at one side of the pivotal center and a substantial part of the spectacle portion is disposed at the other side of the pivotal center in all positions of the semaphore and 45 so that the blade moves downward from the safety to the danger position.

4. The combination, with a semaphore-support, of a semaphore including an integral semaphore-blade and spectacle portion, 50 the semaphore being pivotally mounted on a center at one side of the blade and arranged relatively to its pivotal center so that the blade is at one side of the pivotal center and a substantial part of the spectacle portion 55 is disposed at the other side of the pivotal center in all positions of the semaphore and so that the blade moves downward from the safety to the danger position.

5. The combination, with a semaphore-support, of a semaphore including a semaphore-blade and spectacle portion, the semaphore being pivotally mounted on a center at one side of the blade, the spectacle portion being provided with spectacle-openings 65 adapted to coöperate with a signal-lamp on top of the support and also with a signal-lamp at the side of the support, and with additional spectacle-openings each adapted to coöperate with a signal-lamp in one only 70 of such positions, the semaphore being arranged so that the blade is at one side of the pivotal center when the semaphore is in the safety position and moves downward at the side of the pivotal center from the safety 75 to the danger position.

In testimony whereof I have affixed my signature in presence of two witnesses:

CLARENCE W. COLEMAN.
